UNITED STATES PATENT OFFICE.

WILLIAM B. GREENLEAF AND ERNEST S. ROE, OF PLYMOUTH, MICHIGAN, ASSIGNORS
TO THE MARKHAM AIR RIFLE COMPANY, OF PLYMOUTH, MICHIGAN, A CORPOR-
ATION OF MICHIGAN.

AIR-GUN.

1,268,238.

Specification of Letters Patent. Patented June 4, 1918.

Application filed July 17, 1916. Serial No. 109,775.

To all whom it may concern:

Be it known that we, WILLIAM B. GREENLEAF and ERNEST S. ROE, both citizens of the United States of America, residing at 5 Plymouth, in the county of Wayne and State of Michigan, have invented certain new and useful Improvements in Air-Guns, of which the following is a specification, reference being had therein to the accompanying drawings.

This invention relates to gun constructions and refers more particularly to what is known as air guns or rifles of the break-down type, although the invention in certain 15 of its aspects is not limited to this particular type of gun.

It is among the objects of the invention to provide an improved air gun of that type in which the gun is cocked by what is known as breaking-down the barrel. In guns of 20 this character it is necessary to provide means for locking the two parts of the barrel in true alinement, and the present invention particularly contemplates an improved locking mechanism for this purpose. Other objects of the invention are to provide 25 a longitudinally-adjustable member, operable from a convenient position, for locking the two parts of the barrel in true alinement; to provide a self-contained unit for the spring and locking mechanism; to provide an improved bullet or dart holding means and trigger construction; and in general to provide an improved air gun of the 30 character above referred to.

In the drawings:

Figure 1 is a side elevational view of an air gun embodying our invention;

Fig. 2 is an enlarged longitudinal section 40 through the parts shown in Fig. 1;

Fig. 3 is a cross sectional view on the line $\alpha-\alpha$ of Fig. 2;

Fig. 4 is a perspective view of various parts detached.

Fig. 5 is an enlarged detail of the locking mechanism.

A represents the usual stock of the gun and B the barrel section thereof. At its forward end the stock is provided with a 50 casing C forming the housing for the trigger mechanism, spring and other parts as hereinafter set forth. The barrel is pivoted at D to the forward end of the casing C and the break-down movement of the barrel 55 about the pivot D is utilized for actuating

a lever E, secured at F to a flange G on the barrel. The rear end of this lever extends through a longitudinal slot in the lower part of the casing C, and as the barrel is rocked about its pivot D the lever E forces 60 the spring I back under compression until the hook K² catches upon the latch K' of the trigger K.

The lever is then moved back to an inoperative position as the barrel returns into 65 alinement with the casing C, and the present invention particularly contemplates an improved locking mechanism for holding the barrel in true alinement with the casing. In detail, the mechanism for this purpose comprises a longitudinally-adjustable casing 70 which is movable to a position into the end of the barrel so as to bridge the joint between the barrel and casing. For projecting and retracting this longitudinal-adjustable 75 member we employ the following arrangement.

Positioned within the casing C and longitudinally movable therein is a second casing M which at its forward end fits into a seat 80 N in the rear end of the barrel B. Thus when the casing M is in its forward position it bridges the meeting joint between the barrel and casing C, and holds the barrel in true alinement with the casing. At its rear 85 end the casing M is provided with a transverse slot slightly inclined with reference to the axis of the casing and through this slot there projects a pin N².

This pin also projects through a straight 90 transverse slot in the casing C and at its lower end is pivotally held into position by a screw or bolt O projecting through the stock A.

Whenever it is desired to break-down the 95 barrel for cocking the gun the pin N² is moved laterally and acting on the inclined slot in the casing M will withdraw the casing out of the seat N in the barrel. The barrel is then swung about its pivot D and 100 through the action of the lever E forces the plunger P back against the spring I, putting the spring under compression and moving the hook K² into locking engagement with the latch K' of the trigger. This engagement between the hook K² and the trigger latch will hold the spring I under compression until the trigger is released in the usual manner. After cocking the gun, the 105 barrel is swung back into alinement and 110

locked by adjusting the forward end of the casing M into the seat N, by moving the pin N² over to the opposite end of the transverse slot.

5 As it is necessary that the parts be held in rigid relation when the gun is shot we preferably employ an abutment Q in the end of the casing M which in the alined position of the parts engages a corresponding abutment Q' carried by the true barrel Z and normally spring-pressed rearward by a coil spring R. This abutment Q is fixed on the true barrel Z, which barrel together with the abutment Q', is slidale in the outer barrel 10 section B', the true barrel being of double wall thickness to provide greater strength. Thus the forward adjustment of the casing M will force the abutments into contact and carry the abutment Q' back against the tension of the spring R, this yieldably holding the abutments against each other.

For limiting the forward movements of the abutment Q' I preferably utilize the sight member S which is formed with a 25 flange S' projecting through a slot S⁴ in the barrel a sufficient distance to form the stop for the abutment Q'. It will be noticed that the casing M also forms a housing for the main spring of the gun and this casing is 30 further provided with depending flanges T and T' which have longitudinal slots U and U' forming the bearing in which the pin U² of the lever slides. This casing also carries the trigger, the pin of which extends 35 through bearings V and V' in the flanges T and T'. The usual trigger guard Y is employed, this guard being secured at both ends to the casing C.

For returning the trigger to its operative 40 position after it has been pulled, the spring W is employed, this spring being secured to a flange W² on the trigger and a flange W³ on the casing M, the arrangement being such that the spring is placed under compression 45 when the trigger is drawn backward. The carrying of the trigger mechanism and the spring I by the casing M allows these parts to be assembled and attached as a unit by removing the securing members X and X', 50 and O and withdrawing the stock A from the casing C.

The abutment Q' is swaged or otherwise 55 fixedly secured on the true barrel Z and the abutment Q is provided with an aperture Z' registering with the bore of the true barrel Z, which latter is provided with means for holding the bullet or dart in place. In detail the holding mechanism comprises a light 60 spring member Z² locked in place by the abutment Q' when the latter is fixed on the inner or true barrel Z, which spring exerts

sufficient pressure on the side of the bullets or darts to hold them in position until they are propelled forward by the air pressure produced in the usual manner upon releasing the spring when the trigger is pulled. 65

The arrangement of the spring and plunger within the self-contained unit construction has a further advantage, that all strains and jars are taken by the casing as a unit 70 and not by the individual parts of the gun.

What we claim as our invention is:

1. In an air gun, the combination with two sections pivoted together, of a longitudinally-adjustable member within one of said 75 sections, the end of said member being projectable into the other of said sections, and a spring pressed abutment in the last mentioned section for engaging the end of said member when in its projected position. 80

2. In an air gun, the combination with sections pivoted together, of a plunger in one of the said sections, a casing in said section forming a housing for said plunger, a spring pressed abutment in the other of said 85 sections, and means for adjusting said casing against said spring pressed abutment and into locking engagement with the other of said sections.

3. In an air gun, the combination with 90 sections pivoted together, of means for locking said sections in alinement, comprising a plunger casing in one of said sections and means for projecting the end of said casing into the other of said sections. 95

4. In an air gun, the combination with a barrel section, of a spring pressed abutment therein, and a sight member for said barrel section forming a stop for limiting the end-wise movement of said abutment member. 100

5. In an air gun, the combination with two sections, of relatively movable abutments, one of which is spring-pressed against the other to form a tight joint when the sections are locked in shooting position. 105

6. In an air gun, the combination with sections pivoted together, of means for locking said sections in alinement, comprising a plunger member having a telescopic engagement with one of said sections, means for projecting said plunger member to have a telescopic engagement with the other of said sections, and a spring-pressed abutment between the plunger member and the last-mentioned section adapted to be compressed 110 by the plunger member when in its projected position. 115

In testimony whereof we affix our signatures.

WILLIAM B. GREENLEAF.
ERNEST S. ROE.
